[57] CLAIM

The ornamental design for a visor, as shown and described.

DESCRIPTION

FIG. 1 is a perspective view of a visor showing my new design;

FIG. 2 is a side elevational view thereof, the side not shown being a mirror image of the side shown;

FIG. 3 is a top plan view thereof;

FIG. 4 is a front elevational view thereof;

FIG. 5 is a rear elevational view thereof;

FIG. 6 is a bottom view thereof;

FIG. 7 is a perspective view of an alternate embodiment;

FIG. 8 is a side elevational view thereof, the side not shown being a mirror image of the side shown;

FIG. 9 is a top plan view thereof;

FIG. 10 is a front elevational view thereof;

FIG. 11 is a rear elevational view thereof;

FIG. 12 is a bottom view thereof;

FIG. 13 is a perspective view of another alternate embodiment; and

FIG. 14 is a perspective view of yet another embodiment.
